UNITED STATES PATENT OFFICE

161,789

DECORATIVE ORNAMENT

Nathan M. Purviance, Lewiston, Idaho

Application February 14, 1950, Serial No. 7,928

Term of patent 7 years

(Cl. D29—1)

To all whom it may concern:

Be it known that I, Nathan M. Purviance, a citizen of the United States of America, residing at Lewiston, in the county of Nez Perce and State of Idaho, have invented a new, original, and ornamental Design for a Decorative Ornament, of which the following is a specification, reference being had to the accompanying drawing, forming part thereof.

The figure is a perspective view of a decorative ornament showing my new design.

I claim:

The ornamental design for a decorative ornament, as shown.

NATHAN M. PURVIANCE.
